E. A. JARVIS,

PARKING LAMP.

APPLICATION FILED APR. 26, 1920.

1,368,340.

Patented Feb. 15, 1921.

UNITED STATES PATENT OFFICE.

EDWARD A. JARVIS, OF WEST NEW BRIGHTON, NEW YORK.

PARKING-LAMP.

1,368,340.

Specification of Letters Patent. Patented Feb. 15, 1921.

Application filed April 26, 1920. Serial No. 376,438.

To all whom it may concern:

Be it known that I, EDWARD A. JARVIS, a citizen of the United States, residing at West New Brighton, county of Richmond, State of New York, have invented certain new and useful Improvements in Parking-Lamps, of which the following is a full, clear, and exact description.

This invention relates to improvements in parking lamps for automobiles; in other words, lamps used while automobiles are parked in lieu of the head and tail lights, thereby saving considerable battery energy.

One of the objects of my invention is to produce a combined electric parking lamp, that is to say, a lamp showing red from the rear and white from the front, and a movable mirror, the mirror to be used for daylight driving to observe those behind, together with means to complete the circuit for a bulb, within the lamp, when the mirror is moved out of alinement with the lamp when the lamp is to be used.

Referring to the accompanying drawings:

Figure 1 illustrates a vertical sectional view of a lamp embodying my improvements;

Fig. 2 is an enlarged sectional view, the section being taken on a line 2—2 in Fig. 1;

Fig. 3 is a fragmentary vertical sectional view, the section being taken on a line 3—3 in Fig. 2;

Fig. 4 is a sectional view, the section being taken on a line 4—4 in Fig. 1;

Fig. 5 is a fragmentary vertical sectional view, the section being taken on a line 5—5 in Fig. 1;

Fig. 6 is a sectional plan view, the section being taken on a line 6—6 in Fig. 5; and

Fig. 7 is a modified form of the switch portion of my invention.

As herein embodied, the lamp consists of a base 8 carrying a split expansible shell 9 to hold a front white lens 10 and a rear red lens 11. The lenses 10 and 11 are held in annular channels 12 in said shell. The shell 9 at one end is rigidly secured to the base by a rivet 13 (in this instance), the other end being slotted as at 14 to straddle a clamping bolt 15, which passes loosely through the saddle 16 of the base 8. The upper end of the bolt engages a plate 17 having a threaded opening to engage the threads of the bolt. To secure the lenses, the shell will be clamped thereagainst and

secured in clamped position by tightening the bolt 15. To remove the lenses, bolt 15 will be loosened and the shell spread open sufficiently to allow the lenses to be taken out. The slot 14 permits the shell to be spread. As can be seen, the base 8 is hollow and at its upper end supports a socket 18 for the bulb 19. The socket may be secured in place by molding, as indicated at 20, or otherwise. The mirror 21 is adjustably secured to a hinge block 22 which in turn is pivotally secured to the base 8; in this instance I have provided ears 23, 24, between which the hinge block is located. In this instance, the mirror carries a brace 24^a having an arcuate extension 25 having a slot 26 for the passage of a locking bolt 27, said bolt engaging the block 22. The upper end of brace 24 carries a projection or keeper 28 having an opening therein to be engaged by a teat 29 carried by a latch 30 supported by the shell 9. The radial point of the curved projection 25 will be located at about the point of contact of the upper surface of the keeper 29 and latch 30; hence said mirror can be adjusted toward or away from the lamp when bolt 27 is loosened, without interfering with the engagement of the latch and keeper 29. As the axis of the bolt 27 is in alinement with the axis of the teat 29, the mirror can be adjusted in a vertical plane without interfering with the engagement of the latch and keeper. It will be apparent that the mirror is adjustable in a vertical plane as well as toward or away from the lamp. In this instance, the base 8 carries a threaded nipple 31 to be engaged by a nut 32 to secure the lamp to a mudguard of a vehicle, usually the front left hand mudguard. The mudguard is herein indicated by 33.

One of the features of my invention is to automatically close the circuit for the bulb 19 when the mirror is moved out of alinement with the lamp, when said lamp is to be used (see dotted lines in Fig. 1). To this end I provide a switch operable when the mirror is moved down; in this instance when lowered all the way down. As herein illustrated the switch is operated by the hinge block 22. As herein embodied the switch consists of a block of insulating material 34 carried by the base 8 and contacts 35 and 36, the contact 36 being movable and passing freely through the block. To place the contact 36 in circuit with the bulb, I provide

the socket with a flexible resilient rod 37 which passes through an opening adjacent the inner end of the contact 36. The rod 37 will, of course, be in circuit with one of the 5 conductors within the socket, the other conductor having connected thereto one end of a second wire 39. The wires 38 and 39 will be connected to a source of electrical energy or battery 40 for vehicles having a two wire 10 circuit. For a one wire or ground circuit (see dotted lines 41, Fig. 1), the wire 39 will not be connected, as the base 8 will be a part of the circuit. When the mirror is lowered the hinge block 22 will bridge the 15 contacts 35 and 36 and the lamp will burn. Whether the circuit is two wire or ground, the yieldability of the rod will lend sufficient spring action to the contact 36 to maintain same in firm contact with the hinge 20 block. When not in use the outer end of contact 36 will extend slightly beyond the outer end of contact 35. Instead of employing the contacts 35 and 36, I may use a single movable contact 42 in Fig. 7, which passes 25 through a metal tube 43 but insulated therefrom by a bushing 44. The metal tube will have connected thereto one end of a circuit wire 45. When contact 42 is forced in, the head 46 will contact with tube 43 thereby 30 completing the circuit, for the bulb. The contact 42 engages the rod 47 carried by the socket 48, the same as contact 36 engages rod 37. The opposite circuit wire is indicated by 49. The insulating block 34 may

be held in place by means of a screw 50 (see 35 Fig. 1).

It will also be apparent that the mirror can be adjusted without affecting the hinge block; hence, the switch and hinge block will always coöperate to close the circuit regardless of the position of the mirror relative to the lamp. The weight of the mirror will maintain the hinge block in contact with the switch contacts. 40

Having described my invention, what I 45 claim is:

1. A casing for electric lamps, consisting of a split shell member, an annular channel at each edge thereof to releasably engage a lens, a support, means to secure the shell at 50 one end to said support and means to slidably connect the other end of said shell to said support.

2. A signal device having a white front lens, a red rear lens, a mirror movably 55 mounted adjacent the signal device and normally concealing the red lens, an electric lamp to illuminate the red and white lenses, an open circuit therefor, and means associated with the mirror to close the said circuit 60 when the mirror is moved to expose the red lens.

Signed at New York city, N. Y., this 22nd day of April, 1920.

EDWARD A. JARVIS.

Witnesses:

HARRY VAN TRINSTERM,
MAURICE BLOCK.
